EMANUEL NIELSEN, OF RACINE, WISCONSIN, ASSIGNOR TO HAMILTON BEACH MFG. CO., OF RACINE, WISCONSIN, A CORPORATION OF WISCONSIN

VACUUM CLEANER BRUSH MOUNTING

Application filed October 31, 1928. Serial No. 316,318.

This invention relates to brush mountings and more particularly to means for removably mounting a brush of the non-rotatable type upon a vacuum cleaner. In the present embodiment the mounting is such that the brush is self-adjusting or floating, by which is meant that the brush accommodates itself to any unevenness of the surface to be cleaned so that the ends of the bristles are always in operative contact with said surface.

One of the objects of the invention is to provide a flexible connection between the brush and the vacuum cleaner for the purpose of producing an efficient engagement at all times between the brush bristles and carpet to be cleaned, and means whereby the brush may be easily placed in position and readily removed, as is desirable for the purpose of storing or cleaning the brush.

Another object is to provide a brush mounting in which the vacuum cleaner and the brush are each provided with a single unitary member adapted to cooperate with the other for effecting a dependable but yielding connection between the brush and cleaner without the aid of separate fastening devices. Heretofore brushes have been mounted in vacuum cleaners so as to remain in a fixed position irrespective of the nozzle adjustment, or they have been so mounted as to require separate adjustment when the nozzle is raised or lowered. In the present invention no separate adjustment of the brush is required, as means are provided for adjusting the position of the brush by the adjustment of the nozzle. Not only is the brush automatically adjusted as to its position relative to the floor covering by the adjustment of the nozzle, but its mounting is flexible so that the brush will adjust itself laterally to any unevenness in the floor covering.

Further objects and advantages will appear as I proceed with my specification.

In the drawings:

Figure 1 is a side elevation of a vacuum cleaner embodying my invention, the handle and dust bag being broken away.

Figure 2 is a bottom plan view of the forward part of the device, including the suction nozzle and fan casing.

Figure 3 is a side elevation, enlarged, with the brush and mounting shown in section, the section being taken on the line 3-3 of Figure 5, looking in the direction indicated by arrows.

Figure 4 is a view similar to Figure 3, showing the position of the brush when it is being mounted upon or removed from the cleaner, the sectional parts being taken on the line 4-4 of Figure 5, looking in the direction indicated by the arrows.

Figure 5 is a vertical sectional view of the mounting, taken on the line 5-5 of Figure 3, looking in the direction indicated by the arrows.

Figure 6 is a perspective view showing the two plate members of the mounting detached, one of said members being intended for connection to the body of the cleaner and the other to the brush frame.

Fig. 7 is a rear elevation of the nozzle, partly in section, the nozzle being shown in its lowermost position relative to the floor.

Fig. 8 is a similar view showing the nozzle in raised position.

Fig. 9 is a side elevation of the cleaner, partly in section, with one wheel not shown in order to disclose the nozzle adjusting means.

The following is a general description of the vacuum cleaner to which my invention has been applied. The body of the cleaner comprises a motor housing 15, substantially round, in transverse, vertical cross section, partially closed at its rear end 16, and provided with an outwardly extending flange 17 at its forward end. Ventilating openings in the housing 15 are indicated at 15'. Connected to said flange 17 by screws 18 is a fan casing 19, so arranged that the fan (not shown) will be in axial alignment with the motor shaft. A suction nozzle 20, terminating in a suction mouth 21, is preferably integral with and extends forwardly and downwardly from the fan casing 19. The front wall 22 of the nozzle 20 has an opening therethrough, which is substantially in alignment with the axis of the fan, and said opening is normally closed by a removable plate 23. This opening in the wall 22 is pro-

80

100

vided for the purpose of accommodating a coupling (not shown) for an auxiliary suction tool which may be connected to a flange on the inner surface of the fan casing in 5 such manner that communication between the fan chamber and suction mouth 21 is cut off, and communication established between the auxiliary tool and said fan chamber. Not being a part of this invention, this 10 auxiliary tool connection to the fan casing need not be described in detail.

The body of the cleaner is supported at the rear upon a roller 24 and near the forward end by a pair of rotatably mounted wheels 15 25. A non-rotatable brush 26 is removably mounted externally of the nozzle 20 by means of a bracket 27. A handle 28, having bifurcated ends or spring arms 29 adapted to engage the sides of the motor housing 15, is removably and pivotally mounted on pins 30 which extend outwardly from the sides of said casing 15. The electric current wire 31 connects the motor with a source of power through an extension cord usually carried on 20 25 the handle 28. The fan casing 19 has the usual tubular extension 32, to which a dust bag 33 is removably secured.

In the particular embodiment of my invention shown in the drawings, one part of 30 the brush mounting which it is intended to protect hereby is mounted on the vacuum cleaner by being connected to a wheel-carrying bar which is pivotally connected to the nozzle. Since I have, in this embodiment, 35 provided means for adjusting the relative positions of the wheel-carrying mechanism and the suction nozzle, some movement is also imparted to the brush (which is connected by its mounting to the wheel-carrying bar) 40 when adjustment is being made between the wheel-carrying bar and the suction nozzle, in order to alter the distances between the mouth of the nozzle and the surface to be cleaned.

45 It will be obvious that that part of the brush mounting which is shown as connected to a movable part of the vacuum cleaner, could be connected to a rigid part without departing from the scope of my invention.

50 As shown in the drawings, a bar 34 having rearwardly bent arms 35 carries the wheels 25 which are rotatably mounted thereon at 36. The bar 34 is pivotally connected to the nozzle 20 by a lever 37 having forwardly directed arms 38, said bar 34 and lever 37 being rigidly secured together by rivets 39 or other means. The arms 38 are pivotally connected to depending lugs 40 on the nozzle 20 by a pivot rod 41. The extent of pivotal 55 movement of the lever 37 in one direction is limited by contact between the end 38' of one of the arms 38 with the lower surface of the nozzle 20. A spring 42, wrapped around said rod 41, exerts upward pressure against 60 the lever 37.

Means for adjusting the relative positions of the wheel-carrying bar 34 and nozzle 20, include a lever 43 carrying a nozzle-contact ear 44, one end of the lever 43 being pivotally secured at 45 to the bar 34 and its opposite end being operatively connected with a cam 46 and actuating knob 47. This operative connection is provided by a headed bolt 34' fixed in the wheel carrying lever 34 and extending through a slot 43' in the free end of the lever 43. The cam 46 and knob 47 are rotatably secured to the lever 43 as indicated at 47', with one of the cam edges resting on top of the lever 34. The turning of the knob 47 raises or lowers the nozzle relative to the wheel carrying lever 34. The adjusting means is the subject of a co-pending application filed by Edward Mross, and is not, per se, a part of the present invention and need not be described in greater detail.

Referring now more particularly to those parts constituting the brush mounting which has been indicated as a whole at 27, an angle plate 48 has its vertically disposed member apertured at 49. Its other member, which is substantially horizontally disposed, although slightly inclined downwardly, is preferably provided as shown with three rectangularly shaped apertures 50 and two circular apertures 51, as best shown in Figure 6. The exact number, form and arrangement of these apertures may be varied. In the embodiment shown, the vertical portion of the angle plate 48 is located between the wheel-carrying bar 34 and the pivoted lever 37, and the rivets 39 connect the parts firmly together.

Extending through each of the apertures 51 is a headed bolt 52, the head being disposed under the angle plate 48 and the shank extending upwardly therethrough. On the end of the shank is a washer 53, held against displacement in any desired manner, and between the washer and the upper surface of the angle plate 48 is a coiled spring 54 for the purpose of normally holding the head of the bolt 52 against the under surface of the plate 48, although slightly spaced therefrom by the sleeve portion 55.

The other part of the brush mounting which cooperates with the plate 48 comprises a plate 56 adapted for connection to the frame of the brush 26. In the present embodiment this connection is accomplished through an angular vertically disposed wall 57 apertured at 58, and a reinforcing portion 59 may be provided to engage the upper surface of the brush frame. The plate 56 is provided on its upper surface near its rearward edge with projections 60, formed by slitting the metal at two places for each projection, as indicated at 61, and pressing the metal between the slits upwardly to form projections 60. Said projections are located to register with the recesses 50 in the plate 48 when the parts are in juxtaposition. The rear-

ward marginal portion of the plate 56 is cut out or notched as indicated at 62. The location of the notches is such that when the plate 56 is moved toward the plate 48 to engage the under surface thereof, the notches will be in alignment with the bolts 52 in the apertures, 51.

To bring these parts together, it is necessary to tilt the brush and its plate 56 to clear the mouth of the nozzle, the rearward margin of the plate 56 being moved rearwardly against the under surface of the plate 48 until the marginal side walls 63 of the notches 62 will enter the limited space between the head of the bolt 52 and the under surface of the plate 48 and will tilt the bolt, as the rearward movement is continued, against the tension of the spring 54 (as best shown in Figure 4). After the plate 56 has reached the position shown in Figure 4 and the operator's hold on the brush 26 has been released, the spring 54 will cause the headed bolt to draw the plate 56 upwardly to be substantially parallel with the forwardly extending part of the plate 48. The projections 60 will then engage the apertures 50 and the two parts of the mounting will be securely but removably held together.

In Figure 3 the nozzle is shown in its lowermost adjusted position wherein the wheel-carrying bar 34 has been moved about the pivot 41 to what may be termed a raised position with respect to the nozzle. In this position the top of the brush frame and its plate 56 bear against the under surfaces of the lugs 40, the brush bristles bearing firmly upon the surface to be cleaned, and the mounting plate 56 is not quite parallel to the plate 48 as will be seen from Figure 3. When the adjusting means is actuated to slightly change the pivotal relation between the wheel-carrying bar 34 and nozzle 20, to bring the nozzle mouth 21 further away from the surface upon which the wheels 25 rest, the angle of the forwardly extending part of the plate 48 is slightly altered by the movement of the bar 34, with the result that said plate 48 and plate 56 are substantially parallel to each other.

The construction of the fastening devices 52 and their arrangement in the mounting plate 48 provide a yielding, separable connection between the parts.

The construction described provides a very inexpensive, durable and dependable mounting, efficient for its intended purpose, by means of which all obtrusive connecting parts between brush and nozzle are eliminated and in which no separate fastening devices are required.

Obviously, changes in details of construction may be made without departing from the scope of my invention, and I do not intend to be limited to the precise form shown and de-

scribed, except as pointed out in the appended claims.

I claim as my invention:

1. In a vacuum cleaner having a suction nozzle and floor-engaging supports adjustably secured thereto, a brush of the self-adjusting type, and means for mounting the brush on said suction nozzle, said mounting means including a plate member secured to the floor engaging supports, said plate having a plurality of apertures therein, spring-pressed headed bolts extending through said apertures, and a second plate member secured to the brush, and notched at one margin to register with said headed bolts. 80

2. Means for mounting a brush of the non-rotatable type upon a vacuum cleaner, including a plate member secured to the cleaner, said plate having a plurality of apertures therein, spring-pressed headed bolts extending through some of said apertures, and a second plate member secured to the brush, projections on said plate for engaging the apertures not occupied by said bolts in the first mentioned plate, the margin of 90 said second plate being notched to receive the headed bolts and to be held thereby in yielding engagement with the first mentioned plate. 85

3. Means for mounting a brush upon a 95 vacuum cleaner, including an angle plate member secured to the vacuum cleaner, said plate having a plurality of apertures therein, headed bolts extending through some of said apertures, a coiled spring and a washer 100 upon the shank of the bolt, the spring bearing against the washer and one surface of the plate, a second plate member connected to the brush, and projections on the plate for engagement with the apertures not occupied by said bolts in the first mentioned plate, the second plate having notches registering with said headed bolts, the margins of the plate adjacent the notches engaging the headed bolts and said first mentioned plate member. 110

4. A vacuum cleaner having a suction nozzle, a wheel carrying lever extending longitudinally, rearwardly and exteriorly of the nozzle and adjustably secured to the nozzle, and a nonrotatable brush removably and yieldingly carried by said wheel-carrying lever. 115

In testimony that I claim the foregoing as my sole invention I affix my signature this 22nd day of October, 1928. 120

EMANUEL NIELSEN.
